UNITED STATES PATENT OFFICE.

THOMAS EDWARD GAMBRELL, OF LONDON, ENGLAND.

PLUG-SWITCH.

1,092,037.

Specification of Letters Patent. Patented Mar. 31, 1914.

Application filed November 18, 1913. Serial No. 800,855.

To all whom it may concern:

Be it known that I, THOMAS EDWARD GAMBRELL, a subject of the King of Great Britain, residing at London, England, have 5 invented new and useful Improvements in Plug-Switches, of which the following is a specification.

This invention relates to an improved switch of the plug type applicable for use 10 in connection with resistance boxes, Wheatstone bridges, switchboards, contact makers and breakers and the like.

In the plug switches heretofore generally employed, *e. g.* on resistance boxes, a conical 15 plug has been forced into a socket formed by the adjacent shaped end surfaces of two blocks mounted on the ebonite top of the resistance box. In this arrangement, the blocks themselves are moved 20 slightly during the insertion of the plug between them, so that there is a liability of the plug contacts at the other end of said blocks being disturbed and the contact resistances altered.

25 According to the present invention, in order to prevent disturbance of adjacent plug contacts and to reduce the contact resistance between the coating surfaces of the switch, I make the fixed part of the 30 switch in the form of pieces of metal arranged side by side and insulated from each other, the outer sides of said pieces of metal being shaped to form part of a conical surface adapted to fit a correspondingly shaped

35 conducting surface in a cap, sleeve or ring, hereinafter referred to as a cap. The inner sides of said pieces of metal are preferably shaped to form part of a cylindrical surface adapted to fit around a pin, preferably 40 of metal, secured concentrically in said cap. By this arrangement the lateral forces on the fixed contact pieces are balanced and much larger contact surfaces can be obtained.

45 In the accompanying drawings, I have shown how my said invention can be conveniently and advantageously carried into practice.

In these drawings: Figure 1 is a side elevation of part of resistance box having my 50 improved switches applied thereto, one of said switches being shown in elevation and the other in section, and Fig. 2 is a plan thereof, showing one switch with the cap on and the other with the cap off. Fig. 3 is a vertical central section and Fig. 4 a trans-

verse section on the line *x*, *x*, Fig. 3, showing a modification.

a is an ebonite or other suitable slab forming a top to a resistance-box. 60

b, *c*; *b*, *c*, are pairs of conductors, the lower parts or bases *d*, *d* of which are secured to the slab *a* in any suitable known manner, for example by means of steady pins (not shown), screwed pins *e*, *e* and 65 nuts *f*, *f* and the upper parts of which are shaped to form parts of a cone *g* to fit the correspondingly-shaped interior of a metal cap *h*. The juxtaposed faces of the conductors *b*, *c* are shaped to form parts of a cylindrical surface *j* adapted to fit around a metal pin *k* secured concentrically in the cap *h*. The conductors *b*, *c* are arranged at 70 a suitable distance apart to provide efficient air insulation. Similarly a space *m* 75 is provided between the bases *d*, *d* to facilitate cleaning of the insulating surface of the slab *a*.

It will be seen that when the cap *h* is placed on the conical surface *g* of the conductors *b*, *c* the said conductors will be supported internally by the pin *k* and thus lateral movement thereof will be prevented. At the same time the engaging surfaces *g*, *g* may be made of any required size to reduce 85 the contact-resistance to any desired value. Moreover a further reduction of the contact-resistance is obtained by the engagement of the surfaces *j*, *j* with the surface of the pin *k*. 90

In the modification shown in Figs. 3 and 4 the cap *h*' is provided on its exterior, adjacent to its open end, with a pair of diametrically-opposite lugs which are provided with segmental screw-threads *n*. When the 95 cap *h*' is applied the lugs may be passed down the space *o* between the bases *d*', *d*' and when the cap *h*' is turned the threads *n* will engage with screw-threads *p* on said bases *d*', *d*' in order to hold the cap *h*' 100 tightly on the conductors *b*, *c* for example in cases where the switch is subjected to vibration. In some cases moreover the screw-threads *n*, *p* can be replaced by one or more pins fixed to the bases *d*, *d* and engaging 105 with a corresponding spiral slot or slots in the cap, so that when the cap is turned in one direction the cap is drawn down tightly on to the conductors *b*, *c*.

If desired a screw-thread can be arranged 110 on the pin *k* and engage with corresponding screw-threads on the adjacent surfaces of

the conductors *b*, *c* instead of arranging the screw-threads as shown in Figs. 3 and 4.

What I claim is:—

1. A plug switch comprising fixed conductors arranged at a suitable distance apart and insulated from each other and having their outer surfaces shaped to form parts of a conical surface, and a cap having an interior conducting surface shaped to fit on to said conductors.

2. A plug-switch comprising fixed conductors arranged at a suitable distance apart and insulated from each other, said

conductors having their outer surfaces shaped to form parts of a conical surface ¹⁵ and their inner surfaces shaped to form parts of a cylindrical surface, a cap having an interior conducting surface and a plug mounted concentrically in said cap and adapted to fit the inner surfaces of said ²⁰ fixed conductors.

THOMAS EDWARD GAMBRELL.
